UNITED STATES PATENT OFFICE

141,682

DESIGN FOR A XYLOPHONE

Bernard V. Friedman, Brooklyn, N. Y.

Application April 13, 1945, Serial No. 118,976

Term of patent 14 years

(Cl. D56—1)

To all whom it may concern:

Be it known that I, Bernard V. Friedman, a citizen of the United States, and a resident of Brooklyn, in the county of Kings and State of New York, have invented the new, original, and ornamental Design for Xylophone, of which the following is a specification, reference being had to the accompanying drawing, forming part thereof, in which—

Fig. 1 is a perspective view of the xylophone embodying my design;

Fig. 2 is a side view thereof.

I claim:

The ornamental design for a xylophone, as shown.

BERNARD V. FRIEDMAN.
